UNITED STATES PATENT OFFICE

2,470,492

PICNIC SET

Albert W. Jenkins, New York, N. Y.

Application January 30, 1946, Serial No. 644,327

2 Claims. (Cl. 30—147)

1

This invention relates to improvements in combination implements and tools, and more specifically, to a new and improved picnic set or set of eating utensils which is particularly well adapted for the use by members of the Armed Forces, for tourists, boy scouts, travelers and the like.

The main object of the present invention is the provision of a device of the character described which unites four (or more) implements into a compact set in such a manner that said implements easily can be detached from one another and that they—after use—can be re-united by a simple manipulation so that they require only a minimum of space and that no pieces can be lost.

Another object of the present invention is the provision of a device of the character described which leaves each individual implement free from any protruding parts or connection members, so that each implement can be used in the usual manner, and which does not require a separate container for the set of implements.

Still another object of the present invention is the provision of a device of the character described which, although it consists of only four pieces, is actually a combination of a spoon, a fork, a table knife, a can-opener, a cork screw, and a bottle cap opener, thus uniting six implements to but four and, in addition, constituting also a very practical and space saving holder adapted for holding the implements together when they are not in use and substituting a container for the same.

Yet still another object of the present invention is the provision of a device of the character described which is light in weight, primarily flat, simple in construction, and inexpensive to manufacture, and which has no movable parts that might be subject to any appreciable wear and tear, but which is also sturdy and well adapted to withstand the rough usage to which devices of this kind are frequently subjected.

Further objects of the instant invention reside in any novel feature of construction or operation or novel combination of parts present in the embodiment of the invention described and shown in the accompanying drawing whether within or without the scope of the appended claims and irrespective of other specific statements as to the scope of the invention contained herein.

In the drawing:

Figure 1 is a top plan view of a preferred em-

2

bodiment of my invention as it appears when the implements are not in use;

Figure 2 is a side elevation of the embodiment shown in Figure 1;

Figure 3 shows plan views of the four implements as they appear when they are separated from each other and when they are ready for use; and

Figure 4 is a cross-sectional view on the line 10 4—4 of Figure 2.

Similar numerals refer to similar parts throughout the several views.

In the drawing (Figs. 1 and 2) the numeral 1 denotes a first member, which in the present instance is a can-and-bottle cap opening tool 15 that has a flat U-shaped handle 4. The upper edges of the parallel flanges 2 are inwardly-curved, so as to form a U-shaped channel, and there are notches 3 provided in said inwardly-curved edges. The blade portion which extends from the handle 4 is provided with a fulcrum-shaped recess 5 adapted for engaging the crown cap of a bottle in a well known manner; and its extremity is bifurcated, having a curved cutting portion 6 and a partially inwardly bent portion 7, both of which can be used for the opening of cans in a well known manner.

The second member in the present instance is a table knife having a flat handle 9 from which 30 extends a blade 10. The handle 9 is provided with a notch 8 adapted to engage the inwardly bent portion 7 of the can-opening tool when the blade 10 is inserted into the U-shaped channel formed by handle 4. I prefer to provide the 35 knife handle 9 also with a longitudinal recess 11 and with a cork screw 10a which is pivoted to handle 9 at 12 adjacent the recess 11.

The third member in the instance shown is a fork 17 from which extends a flat handle 13 40 that is provided at one side with a knob 15 and that is adapted for being inserted into the U-shaped handle 4 above the knife blade 10.

The fourth member in the present instance is a spoon 18 having a flat handle 14 which is 45 provided with an aperture 16 and with knobs 19. Handle 14 is adapted to be inserted into the U-shaped handle 4 between the inwardly curved edges of the flanges 2 and the fork handle 13; thereby the knob 15 engaging the aperture 16, and the knobs 19 engaging the notches 3.

Since the curved bowl of the spoon 18 extends over the fork 17, the pointed prongs of the fork 17 are covered entirely, so that the device can be carried in a pocket or the like without any possibility of injuring the person carrying the de-

vice. If the implements are in the position shown in Figs. 1, 2 and 4, the tip of the bowl of spoon 18 rests against and presses upon the rear end of the knife handle 9, and since the longitudinal implements (knife, fork and spoon) are somewhat resilient, the knobs 19 are safely held in the notches 3, so that the implements cannot disengage themselves from one another inadvertently. In order to disengage the implements from one another, it is necessary to press upon the spoon handle 14, so that the knobs 19 leave the notches 3, and then the spoon and the fork can be pulled out of the U-shaped handle 4, whereupon the knife handle 9 is lifted up so that its notch 8 can be disengaged from the inwardly bent portion 7.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

Having thus described my invention, what I claim and desire to secure by Letters Patent in the United States is:

1. The herein-described implement comprising one member having a can-and-bottle-cap-opening tool at one end and having a U-shaped handle portion whose upper longitudinal flange edges are inwardly-curved, a second flat member having on its handle portion a notch which engages an inwardly bent portion of said can-opening tool when said second member is slid into the U-shaped handle portion of said first member, a third member having a flat handle portion which has a knob at one side and which is adapted to be slid into the U-shaped handle portion of said first member above said second member, and a fourth member having a curved main portion and

a flat handle portion which is provided with knobs on one side and with an aperture adapted for engaging the knob on said third member when the handle of said fourth member is inserted between the third member and the inwardly curled edges of the U-shaped handle portion of said first member, said inwardly curled edges being provided with recesses adapted to engage the knobs on one side of the handle portion of said fourth member, all substantially as described.

2. The herein-described implement comprising a can-and-bottle-cap-opening tool having a U-shaped handle portion whose upper longitudinal flange edges are inwardly-curved, a knife having on its handle portion a notch which engages an inwardly bent portion of said can-opening tool when the blade of said knife is slid into the U-shaped handle portion of said can-opening tool, a fork having a flat handle portion which has a knob at one side and which is adapted to be slid into the U-shaped handle portion of said can-opening tool above said knife, and a spoon having a flat handle portion which is provided with knobs on one side and with an aperture adapted to engage the knob on said fork when the handle of said spoon is inserted between said fork and the inwardly curled edges of the U-shaped handle portion of said can-opening tool, said inwardly curled edges being provided with recesses adapted to engage knobs which are on one side of the handle portion of said spoon, all substantially as described.

ALBERT W. JENKINS.
